FIGS. 5 and 6 are respectively front and rear elevational views thereof.

FIG. 5

FIG. 6

FIG. 1

FIG. 2

FIG. 3

FIG. 4

UNITED STATES PATENT AND TRADEMARK OFFICE
Certificate

Patent No. D.294,221

Patented: Feb. 16, 1988

On petition requesting issuance of a certificate for correction of inventorship pursuant to 35 U.S.C. 256, it has been found that the above-identified patent, through error and without any deceptive intent, improperly sets forth the inventorship. Accordingly, it is hereby certified that the correct inventorship of this patent is:

Steven J. Sheftel and Huang Tieh-Jung.

Signed and Sealed this Eighteenth Day of December 1990.

WALLACE R. BURKE
